US0D1090587S

(12) **United States Design Patent** (10) **Patent No.:** **US D1,090,587 S**
(45) **Date of Patent:** **** Aug. 26, 2025**

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventors: **Bowon Kim**, Suwon-si (KR); **Jiyeon Yoo**, Suwon-si (KR); **Youbi Seo**, Suwon-si (KR)

(73) Assignee: **SAMSUNG ELECTRONICS CO., LTD.**, Gyeonggi-Do (KR)

(**) Term: **15 Years**

(21) Appl. No.: **29/922,913**

(22) Filed: **Dec. 27, 2023**

(30) **Foreign Application Priority Data**

Jul. 7, 2023 (KR) 30-2023-0026211

(51) **LOC (15) Cl.** **14-04**

(57) **CLAIM**

The ornamental design for a display screen or portion thereof with graphical user interface, as shown and described.

DESCRIPTION

The FIGURE is a front view of a display screen or portion thereof with graphical user interface, showing our new design.

The outermost broken lines in the FIGURE depict the display screen or portion thereof that forms no part of the claimed design. The remainder of the broken lines in the FIGURE depicts portions of the graphical user interface that form no part of the claimed design.

The contrast shown in grayscale in the FIGURE represents a contrast of appearance.
